VALVE COMPENSATING MECHANISM

Bror G. Anderson, Syracuse, N. Y.

Application July 1, 1931, Serial No. 548,176

1 Claim. (Cl. 123—90)

This invention has for its object a particularly simple, compact and efficient valve mechanism for the valves of internal combustion engines by which a sufficient, but not excessive, tappet clearance is maintained under all temperatures, and which clearance is taken up without tappet noises.

The invention consists in the novel features and in the combinations and constructions herein-after set forth and claimed.

10 In describing this invention, reference is had to the accompanying drawings, in which like characters designate corresponding parts in all the views.

Figure 1 is an elevation of this compensating mechanism, the same being shown as applied to an over-head valve mechanism, fragmentary portions of the engine being shown.

Figure 2 is an enlarged, fragmentary view, partly in section, of parts seen in Figure 1.

20 Figure 3 is a sectional view on line 3—3, Figure 2.

Figure 4 is a sectional view of this valve compensating mechanism applied to upwardly lifting valves, as the valves of an L-head engine.

25 Figure 5 is a sectional view on line 5—5, Figure 4.

It is well known that in internal combustion engines, the valve tappet clearance, or the clearances in the valve operating mechanism, vary as 30 the engine heats up and the cylinders elongate, and that some means is necessary, or at least highly desirable, to take up the clearance without tappet noises or with minimum noise.

The invention comprises generally a compensating mechanism including a lever interposed 35 between the driving member or push rod and the driven member which operates the valve, the lever being pivoted to one of said members, and having an arm for thrusting against the other 40 with a lost motion connection between the lever and the member to which it is pivoted, the lost motion connection being located nearer the axis of the lever than the point on said arm where the thrust of the driving member is received.

45 More specifically, this invention comprises a compensating mechanism preferably having a wedging or rolling in action, that is, an action in a lateral direction or a direction at an angle to the direction of movement of the members 8 and 50 5, for taking up the clearance under all conditions, the wedge receiving the thrust of the driving member or lift rod of the valve mechanism and first serving to take up the clearance with a wedging action, and a spring for acting in opposition to the driving member or push rod to re-

turn the wedge to its normal position and maintain the normal clearance when the valve closes, the wedge being operated to take up the clearance during the opening operation of the valve mechanism. More specifically, the wedge means comprises a wedge or cam having a movement about an axis.

In Figures 1 and 2, I have shown my invention as applied to an over-head valve mechanism.

10 1 designates the valve, and 2 the valve seat of a cylinder. 3 is the valve stem, and 4 the springs which close the valve head against its seat.

5 is a rocker lever, or a driven member of the valve mechanism, this being pivoted at 6 between its ends to a suitable support 7 mounted in any 15 suitable manner on the head of the engine cylinder.

8 designates the driving member or lift rod of the valve mechanism, this being guided in a suitable bushing 9 in the top wall of the crank case 20 10 of the engine, and coacting at its lower end with a cam 11 on the cam shaft of the engine. The driving member or push rod 8 thrusts toward the rocker arm lever 5, but the motion is transmitted to said lever through the compensating mechanism.

The take-up mechanism comprises a lever 12 pivoted to a depending end portion 13 of the lever 5 and having a surface 14 coacting with the surface 15 on the lever 5, the lever 12 having an arm 30 extending laterally relatively to the push rod and provided with means for coacting with the end of the push rod to receive the thrust therefrom. The take-up means further includes a spring 16 interposed between the lever 12 and the lever 5. One 35 of the surfaces 14, 15 is an eccentric or cam surface, and the other is a follower surface. Preferably, the surface 14 on the lever is the eccentric or cam and also the follower surface 15, as here shown, extends around or embraces the cam surface to a considerable extent, although it may be of relatively small area as a little more than a point.

As seen in Figure 2, there is a clearance at 17 45 between the cam surface 14 and the cam surface 15. The spring 16 is of sufficient weight or strength to normally hold or press the lever 12 against the end of the push rod 8, but is a relatively light spring compared with the valve 50 springs 4.

In operation, the parts are normally in the position shown in Figure 2. As the cam 11 lifts the push rod 8, as shown in Figure 2, the lever 12 is moved upwardly about its axis against the spring 16, and in so doing, rolls or moves the cam so that 55

its eccentric portion first takes up the clearance 17 and then the additional thrust of the push rod 8 is transferred to the lever 5 through the solid connection formed between the compensating lever 12 and the rocker arm lever 5, this movement opening the valve head 1.

When the cam 11 clears, or moves out of engagement with the push rod 8, the springs 4 react to close the valve, and the spring 16 reacts during the retrograde movement of the push rod 8 and holds the engaging means on the lever 12 against the end of the push rod, and in so doing, moves the lever 12 downwardly about its pivot to again provide the clearance at 17. This clearance 17 will vary slightly due to the temperature of the engine, and changes and conditions ordinarily brought about by expansion and contraction of the engine cylinder under working conditions. The compensating lever 12 has an eccentricity for the reduction of the valve tappet clearance at a ratio of approximately 10 to 1. Assume that the clearance is .010 of an inch before the compensating spring is inserted, and that the compensating lever 12 has taken up the clearance at 17, then the compensating spring is inserted and the spring adjusted. The valve tappet clearance is then reduced to nothing, due to the pressure of the compensating spring, which at all times keeps the engaging means or lever 12 in contact with the push rod 8, but a clearance is created at 17 and on account of the ratio of 1 to 10 mentioned above, this clearance 17 will only be .001 of an inch. As the valve lifter rod moves upwardly under the action of the cam shaft, the clearance 17 decreases to zero. Owing to the wedge, or eccentric, the taking up of the clearance is gradual as the curves, or convex and concave surfaces, of the cam and the driven member or lever 5 come together to take up the clearance with a sliding movement, instead of with an impact, so that the compensating mechanism has a quiet action.

The means on the lever 12 for receiving the thrust of the push rod is preferably adjustable, and here shown as a screw 18 threading through the arm 12 with its lower end arranged to engage the upper end of the push rod, a lock nut 19 being provided for holding the screw in its adjusted position. The spring 16 at its lower end encircles the head of the screw 18, and at its upper end thrusts against an abutment 29 threading into the lever 5, this abutment being hollow in order to provide a work hole 21 through which the screw 18 is accessible.

The compensating lever 12 is here shown as provided with a bifurcated hub or cam mounted on a pin 22 mounted in the depending portion 13 of the lever 5, the portion 13 extending between the bifurcations of the lever 12. The cam surfaces 14 are provided on the periphery of the bifurcated hub of the lever 12 and there are two cam surfaces 15 on the lever 5 coacting with the surfaces 14 on the hub of the lever 12. The pivot pin 22 is shown as held in position by snap rings 25 at the ends thereof. Also, the pivot is provided with oil grooves 26 and the hub of the lever 12 and the adjacent portion of the lever 5 provided with communicating oil ducts 27. The oil is supplied in any suitable manner.

In Figures 4 and 5, this compensating mechanism is shown as applied to a valve mechanism such as are used in L head engines.

41 designates the valve head, 42 the valve seat, 43 the valve stem, and 44 the valve spring.

45 designates the driven member which in-

stead of being a lever, is a reciprocally movable push rod or plunger guided in any suitable manner in a guide 46. The push rod 45 is provided with a screw 47 extending axially thereof which thrusts against the end of the valve stem. This screw 47 also serves as an abutment for the compensating spring 56.

48 is the lift rod guided in a suitable bushing 49 in the top wall of the crank case 50 and coacting at its lower end with the cam 51 on the cam shaft.

52 is the compensating lever pivoted to a laterally extending arm 53 on the driven member or plunger. The cam has an eccentric cam surface 54 coacting with a complementary surface 55 on the arm of the push rod 45.

56 is a compensating spring interposed between the screw 47 and the arm of the compensating lever 52. 58 is an adjusting screw in the arm of the lever 52 and thrusting against the upper end of the driving member, or lift rod 48 and is provided with a head 71 by which it is adjustable.

The guide 46 is supported, as shown in Figure 5, by brackets 72 extending upwardly from the guide bushing 49 for the lift rod 48, and the lever 52 and arm 53 of the plunger 45 extend between these brackets.

In order to hold the member 45 from turning and also to guide the same, the arm 53 of the driven member 45 is provided with a guide rod 75 slidable in a vertical passage 76 formed in the bushing 49, the passage 76 having a vent hole 77 into the crank case to prevent the passage from becoming air bound. The operation of the form shown in Figures 4 and 5 is the same as that shown in Figures 1 and 2. The clearance between the cam surfaces 54 and 55 is adjusted by means of the screw 58, and the clearance between plunger 45 or screw 47 thereof and valve stem 43 is taken up by spring 56. During the lifting operation of the cam 51, the clearance between the surfaces 54 and 55 is taken up by the pivotal movement of the lever 52 upwardly against the spring 56, and after the clearance is thus taken up, the lever 52 and member 45 are thrust upwardly as a unit against the end of the valve stem 43, thus opening the valve.

When the cam 51 passes out of engagement with the lift rod 48, and the valve spring 44 is free to react, the parts return to their normal position, and the spring 56 moves the lever 52 downwardly on its pivot relatively to the member 45 thus again forming the clearance between the surfaces 54 and 55.

In either embodiment of my invention, the normal clearance varies only slightly under all temperature conditions, and is taken up by a wedging or rolling in action.

What I claim is:

In an operating mechanism for valves of internal combustion engines, the combination of two motion transmitting members, one being a push rod, and compensating means for transferring the movement of the push rod to the other member, the other member having an arm extending at an angle to the push rod, said compensating means including a lever pivoted to the outer end of said arm and extending under the same towards the push rod and formed with a cam surface eccentric with its pivotal axis, said arm being formed with a surface with which the cam surface coacts and a spring interposed between said arm and the compensating lever.
